E. M. BENNETT,
REFLECTING LAMP SHADE AND GLOBE,
APPLICATION FILED DEC. 20, 1918.

1,354,158.

Patented Sept. 28, 1920.

Inventor:

Ernest Malcolm Bennett

By *Paul Poincier*

Attorney

UNITED STATES PATENT OFFICE.

ERNEST M. BENNETT, OF PRAHRAN, MELBOURNE, VICTORIA, AUSTRALIA.

REFLECTING LAMP SHADE AND GLOBE.

1,354,158.

Specification of Letters Patent. Patented Sept. 28, 1920.

Application filed December 20, 1918. Serial No. 267,626.

To all whom it may concern:

Be it known that I, ERNEST MALCOLM BENNETT, a subject of the King of Great Britain and Ireland, residing in the city of Prahran, 5 a suburb of the city of Melbourne, in the county of Bourke, State of Victoria, Commonwealth of Australia, and whose post-office address is 115 Union Street, Windsor, in the said city of Prahran, have invented 10 certain new and useful Improvements in Reflecting Lamp Shades and Globes, of which the following is a specification.

This invention relates to globes and shades for use with electric incandescent or other 15 lamps and its object is to provide a reflecting globe or shade which will materially increase the illuminating effect of the lamp by reflecting and refracting the light rays in such a manner that their maximum value 20 is availed of and a brilliant result is obtained.

The invention is particularly advantageous for display purposes such as the illumination of buildings, showcases, window 25 fronts, and such like positions where brilliant effects are desired.

The invention consists essentially in forming a shade or globe of transparent glass the exterior of which is silvered or otherwise 30 treated to produce a reflecting surface, while the interior of the shade is provided with a series of jewel shaped or multi-sided projections having inclined facets which are arranged to distribute or refract the reflected rays from the lamp or illuminating 35 agent to various different directions thus greatly increasing the brilliance and effectiveness of the light.

Referring to the drawings which form 40 part of this specification:—

Figure 1 is a view of a shade constructed in accordance with the invention portion being broken away to illustrate one form of the refractive projections on the inner 45 face of the glass.

Fig. 2 is a plan of Fig. 1 portion being broken away to illustrate the cross sectional contour of the projections.

Fig. 3 is an enlarged view of portion of the internal face of the shade seen in Figs. 1 and 2.

Fig. 4 is a view of another form of shade or globe in which the internal projections are of pyramidal form with straight or 55 flat sides.

Fig. 5 is a plan of Fig. 4 part being broken away.

Fig. 6 is an enlarged view of portion of the interior face of the shade or globe seen in Figs. 4 and 5.

Fig. 7 is an enlarged vertical section of portion of a shade showing the concave formation applied to the pyramidal projections.

Fig. 8 is a section on line A—A of Fig. 7. 65

In accordance with the invention the globe or shade is formed of transparent glass of any desired shape, design or color.

The outer surface 2 of the glass is plain or smooth and to it is applied by any well known means a suitable reflecting agent such as quicksilver. A particularly suitable formula for this preparation is as follows:—

(a) Nitrate of silver—175 avoirdupois grains, distilled water 10 avoirdupois ozs.; 70
(b) nitrate of ammonia—262 avoirdupois grains, distilled water 10 avoirdupois ozs.;
(c) pure sugar candy— $\frac{1}{2}$ avoirdupois oz., distilled water 5 avoirdupois ozs.; (d) tataric acid—50 avoirdupois grains, dissolved 80 and boiled in a flask for ten minutes and when cool 1 avoirdupois ounce of alcohol and distilled water sufficient to make up 10 ounces added.

For use equal parts of (a) and (b) are 85 mixed together, and equal parts of (c) and (d) are mixed in another measure. These two mixtures are then intermixed in the silverying vessel.

The shade or globe after being carefully 90 cleaned with soda and well rinsed with clean water is suspended with its outer face downward in the silverying solution where it is allowed to remain for from 20 to 80 minutes according to weather conditions. The shade 95 is then withdrawn and the silverying solution allowed to dry thoroughly on the glass.

After the outer surface of the shade has been thus treated I preferably apply a protective outer coating or backing of suitable 100 material such as an elastic varnish. A suitable preparation for this purpose may be formed by dissolving and mixing together the following ingredients:

Dammar gum	10 parts	105
Asphalt	3 parts	
Gutta percha	5 parts	
Benzol	75 parts	

This solution is poured over the silvered 110

surface of the shade which is then moved to and fro until the varnish is distributed evenly over the whole surface.

In conjunction with the outer reflecting surface which may be produced by the above or any other means, the shade is provided on its interior with a series of projections 3 which protrude inwardly toward the center of the shade. These projections 10 may be of any suitable design or contour such for instance as shown in Figs. 1 to 3 where they are formed of a diamond or jewel shape having flat truncated surfaces or tables indicated at 4 and a multiplicity 15 of inclined sides or facets 6 which are adapted to refract or distribute the reflected rays from the lamp in various different directions. The inclined sides or facets may be plane, or they may be of concave formation, 20 the latter construction being illustrated in Fig. 3.

Another example of the shape which the projections 3 may take is shown in Figs. 4, 25 5 and 6 where they are of a plain pyramidal form and provided with inclined flat sides or facets which may be plane, as represented at 7 in said figures, or of concave formation, as indicated at 8 and 9 in Figs. 7 and 8.

30 In Figs. 7 and 8 the silver or reflecting medium is indicated on the outer plain surface of the glass by the numeral 10 and the varnish or other protective backing is indicated at 11 to clearly show the relative features of the invention.

By thus treating a transparent lamp shade or globe a highly effective and brilliant result is obtained. The rays from a lamp thus inclosed are reflected back by the outer reflecting surface of the shade and then 40 thrown out in a variety of directions by the inclined sides or facets of the projections 3 thus greatly enhancing the illuminating power of the lamp. The invention furthermore does not greatly increase the cost of 45 production of the shade or globe which may obviously be made in any size, shape or color required.

Having now described my invention what I claim as new and desire to secure by Letters Patent is:—

1. A lamp shade or globe of transparent glass, having a reflecting medium covering its exterior surface, and provided on its interior with integral, inwardly - extending 55 jewel-shaped projections having flat, truncated surfaces or tables and a multiplicity of inclined sides or facets, said sides or facets being of concave formation.

2. A lamp shade or globe of transparent 60 glass, having a reflecting medium covering its exterior surface, and provided on its interior with integral, inwardly - extending multi-sided projections, the sides of said projections being of concave formation. 65

In testimony whereof I affix my signature.

E. M. BENNETT.
